UNITED STATES PATENT OFFICE.

CARL THEODOR AUGUST HERMANN WIEDLING, OF NORTH BERGEN TOWNSHIP, HUDSON COUNTY, NEW JERSEY, ASSIGNOR TO THE WIEDLING MANUFACTURING COMPANY, OF NORTH BERGEN, NEW JERSEY, A CORPORATION OF NEW JERSEY.

PROPELLER.

1,129,934.

Specification of Letters Patent. Patented Mar. 2, 1915.

Application filed June 12, 1908. Serial No. 438,037.

To all whom it may concern:

Be it known that I, CARL THEODOR AUGUST HERMANN WIEDLING, a citizen of the United States, and a resident of the township of North Bergen, county of Hudson, and State of New Jersey, have invented a new and Improved Propeller, of which the following is a full, clear, and exact description.

10 The invention relates to rotary propellers for ships, balloons, flying machines and similar vehicles, and it is also of equal usefulness for other devices and machines, as a rotor for steam, water or other fluid turbines, pumps, air compressors, blowers, fans, etc.

The object of my invention is to secure a greatly increased power efficiency and to reduce vibrations.

20 To enable others skilled in the art to make and use my invention, I will now describe it, by reference to the accompanying three sheets of drawings, in which—

Figure 1 is a stern view of my propeller as it would appear when installed for the propulsion of a ship or flying machine; Fig. 2 is a view, in plane development, of one of the blades of my propeller, with four blades, giving the correct least widths required and as found by calculation; Fig. 3 is a view, in plane development, of one of the blades of my propeller, with four blades, wherein the widths at the different radii, are made twice as great throughout as those in Fig. 2, and 35 which corresponds in size, to the blades shown in all the figures, except those of Figs. 2 and 5; Fig. 4 is a starboard view of my propeller, in which one half of the stationary shrouding is removed and shown in section on dotted line Y—Y, of Fig. 1; Fig. 5 shows, in plane development, the cross-section of the propeller blade at the outer radius and corresponding to the least blade widths required, as per Fig. 2. It also shows 40 the degree of the angular position of this blade section, in reference to the axis of the propeller, the direction of which is indicated by the line X—X, and it further shows, in

plane development of the co-axial cylindrical cross-section, the area of the water current, which is subject to dynamic pressure; Fig. 6 is a diagram, showing in plane development, the cross-sections of the propeller blade, at the different radii from the axis of the propeller, as indicated by the circular arcs 3, 4, 5, and 6—10 in Fig. 1. It also shows the degree of the angular position of these sections, in reference to the axis of the propeller, the direction of which is indicated by line X—X, however, without showing them in their true, relative position. Further, Fig. 6 shows, in plane development, the co-axial cylindrical cross-sections, of the water current, which are subject to dynamic pressure and which pertain to the 55 blade sections at the different radii; Fig. 7 is a diagram of the dynamic pressures, generated by the deflection, of the water current, within the entire range of the driving face of the propeller blade and throughout 60 of the different distances from the driving face of the blade and at the different radii of the propeller and at the co-axial cylindrical, cross-sectional areas of dynamic pressure, pertaining to the different blade sections. 65

This diagram refers particularly to the wide blades adopted in Figs. 1, 3, 4, 5, 8 and 9, and not to the blade of least width, shown in Figs. 2 and 5; Fig. 8 is a diagram, in plane development, of the co-axial cylindrical sections through the driving face of the blade, at the different radii, and explains the method used for locating the blade sections axially and circumferentially; Fig. 9 is a plane development of the co-axial cylindrical cross-section through the propeller blade, enlarged, so as to better show the special features thereof; and Fig. 10 is an enlarged cross-section, through the shrouding of the propeller blade, on line Z—Z of 70 Fig. 4. 75

The ship propellers and similar propellers, known at present, are very inefficient, mainly due to pressure losses caused by the partial motion of the water current, radially outward as well as radially inward, while with- 85 90 95

in active range of the driving face of the blade. This radial motion, in properly proportioned propeller blades, is almost entirely due to the dynamic pressure generated by the deflection of the water current, and only to a very slight degree due to centrifugal action caused by the rotation of the water with the propeller, contrary to the ordinary supposition. Loss of efficiency of 10 a lesser degree is also due to the friction of the water current on the propeller blades, particularly when the latter are made of a much greater width, than required, either for strength or effect. Other losses are 15 caused by the faulty cross-sectional form of the blades, either by the use of blades of true and uniform pitch, surface, or through the faulty curvature of the driving face of the blade or the back thereof, or by the 20 wrong form of the leading edge of the blade.

I have found through experimental and mathematical research that the ideal propeller is one in which the stream lines of 25 the water current while within the range of action of the driving face of the blade are guided within lines of constant distance from the axis of rotation of the propeller, or within cylindrical surfaces concentric 30 with the axis of the propeller. Further, in this manner I have found that for maximum efficiency the pitch at the leading edge of the propeller blade must be equal at all the radial distances from the axis of rotation; 35 further, the pitch velocity at the leading edge of the blades must be made equal to the relative axial velocity of the water current so as to lead the latter into perfect tangential contact with the driving face of the 40 blade. By "pitch velocity" I mean the velocity with which any point though stationary circumferentially and radially, will travel in a straight line axially, while remaining in contact with the driving face of the 45 propeller in motion. The term "cylindrical cross-section" is used herein in reference to the blade, or the driving face thereof, or the areas of dynamic pressure, to denote the cross-sections thereof, as established 50 within the surfaces of cylinders, coaxial with the propeller and corresponding to the radii 3, 4, 5, to 10 of the propeller and as indicated by the circular arcs of Fig. 1. The widths of the blades, the circumferential widths and the relative widths of the 55 water current, the radii of curvature of the driving face of the blade, all are straight line measurements, taken within the plane development of these co-axial cylindrical cross-sections. The conditions set forth 60 herein, are those required for the maximum performance and quietness of running of my propeller and therefore, the pitch velocity,

at the leading edge of the blade, is assumed as equal to the axial velocity of the water current, relative to the propeller. Thereby the water current enters the normal plane of the propeller at an angle, which is equal to the pitch angle, X , at the leading edge of the driving surface of the blade. Further, herein is assumed, as is the general practice, that the blades, of the propeller, are spaced equidistant circumferentially, and that they are located within the same normal axial plane and that they are of the same size and form. Under the term "circumferential width of the water current, acting upon one blade," I mean the distance, in circular measurement, within a plane normal to the axis of the propeller, of similar 80 points of the leading edges of two adjacent blades and of the same radial distance from the axis of the propeller. The total circumferential width of the water current, at any radius, r' , of the propeller, is $2r'\pi$, and therefore the circumferential width, w , of the water current acting upon one blade of the propeller, having n' , number of equally spaced blades, is equal to the total circumferential width of the water current, divided by the number of blades, or

$$w = \frac{2r'\pi}{n'}$$

Under the term, "relative width of the water current," I mean the width thereof, as measured within the plane development of the co-axial cylindrical cross-section, at any radius of the propeller and normal to the driving face line. This is the normal distance between the tangents, of the driving face lines, at the leading edges of two adjacent blades, as measured within the plane development of the co-axial cylindrical cross-section pertaining to any radius of the propeller, because the water current enters between each two adjacent blades obliquely, at the pitch angle, X , of the leading edge of the blade. Therefore, the relative width, W , is a function of the circumferential width of the water current, acting upon one blade, and the pitch angle, X , of the leading edge of the blade, or

$$W = w \sin X,$$

or

$$W = \frac{2r'\pi}{n'} \sin X.$$

Further, I have found that the blades of the propeller must be made of a pitch increasing uniformly from the leading edge to the rear edge, or, in other words, the driving face of the blades must, in any co-axial cylindrical cross-section concentric with the axis of the propeller, appear in

plane development thereof as a true circular curve. Further, I have found that the degree of curvature of the driving face of the blade in co-axial cylindrical cross-section thereof, as afore mentioned, affects the performance of the propeller greatly, and that the radius of curvature thereof must be at least equal to the relative width of the water current passing between two adjacent blades, whereby the relative width of the water current is measured on a line normal to the cross-sectional line of the driving face of the blade. On this basis I have found that very efficient propellers can be constructed with comparatively very narrow blades, and that, in most cases, the blade widths must be selected rather for the purpose of sufficient strength and keenness of cross-section than for the purpose of gripping the water current. Further, I have found that by means of the correct selection of the curvature of the driving face of the blade in the co-axial cylindrical cross-sections thereof, the dynamic pressures generated through the deflection of the water current can be augmented or increased or reduced and controlled so as to very closely balance the dynamic pressures in the different layers of the water current, in radial direction. Further, I have found that the pressure generated through the deflection of the water current primarily acts in the direction normal to the cross-sectional curvature of the blade, and that on this account the blade may be curved in a combined circumferential and axial direction so as to completely prevent the passage of water toward the axis of the propeller. Further, I have found a novel and correct form of shrouding, of the least frictional area, however of sufficient area to completely prevent the escape of water from the current under dynamic pressure to the outside of the circumference of the propeller. Finally, I have combined these features of my invention into a very practical form of a propeller, which is adapted to suit all conditions found in general practice.

In all of the drawings, except in Fig. 7, the figures of reference from 0 to 10 indicate the relative radial distances of the blade sections from the axis of rotation of the propeller. In Figs. 1 and 4, 11 is the stern frame and 12 the stern bearing of a ship, flying machine or other device to be driven by the propeller 21. The propeller shaft 22 is journaled within the stern bearing 12 and is secured on its outer end within the hub 23 of the propeller. The hub 23 has on its rear face the cap 13 to prevent cavitation on the back face thereof, and is provided, in that embodiment of my invention illustrated, with the four propeller blades 24, each of which

has on its outer edge a shrouding 25 of cylindrical curvature, corresponding to the outer radius of the propeller blade.

Concentrically surrounding the propeller and attached to the branches 26, 26, of the stern frame 11 is located the stationary cylindrical shrouding 27. The propeller exemplified is of left hand pitch and has a pitch of 1.57 times its outer diameter at the leading edges of the blades, which are of uniformly increasing pitch so as to give a pitch of 2.23 times the outer diameter of the propeller at the rear edge of the blades, and, therefore, a mean pitch ratio of 1.88. The mean pitch ratio is obtained from the mean pitch angle of the outer cross-section of the driving face of the blade. The pitch ratio of 1.57 at the outer leading edge of the blade corresponds to a pitch angle of $26^{\circ} 33' 10''$; the pitch ratio of 2.23 at the rear outer edge of the blade corresponds to the pitch angle of $35^{\circ} 22' 6''$. Therefore, the mean pitch angle of the outer edge of the driving face of the blade is $30^{\circ} 57' 38''$, to which corresponds the pitch ratio of 1.88, which is the mean pitch ratio. The arrow on the upper left hand of Fig. 1 indicates the direction of rotation of the propeller for the forward motion of the ship. The blades 24 of the propeller are curved in a helically pitched spiral of opposite helical and opposite spiral pitch to the pitch of the driving face of the propeller blades, as is evident in Figs. 1 and 4; or, in other words, the blades of the propeller with driving faces of left-hand pitch, as shown herein, are curved in a helically pitched spiral of right-hand helical and right-hand spiral pitch. Otherwise, in a propeller having driving faces of right-hand pitch, the blades are curved in a helically pitched spiral of left-hand helical and left-hand spiral pitch. By a helical pitched spiral is understood a line generated by the progressive rotation of a point around the axis of the propeller, which point contemporaneously increases its distance from the said axis. By right-hand spiral pitch is understood the direction of the line generated by the progressive clockwise rotation as seen from the stern of the vessel, of a point around the axis of the propeller, with a constantly increasing distance from the axis. Likewise, by left-hand spiral pitch is understood the direction of a line generated by the progressive counter-clockwise rotation as seen from the stern of the vessel, of a point around the axis of the propeller with a simultaneously increasing distance from the axis of the propeller.

I have found that the ideal propeller in which the water current is not subject to centripetal or centrifugal motion, requires very narrow blades only to completely and

perfectly act on the water passing through the propeller. In a four-bladed propeller of the pitch shown in Figs. 1 and 4, and mentioned dimensionally hereinbefore, the ideal 5 blade would have to be of a width of 0.056 times the outer diameter of the propeller at its widest part, near radii 7 and 8 of Fig. 2, in which the ideal blade widths are indicated in decimal fractions of the outer diameter of the propeller. However, these narrow blades can in most cases not be used actually for the reason of lack of strength, or otherwise, when made sufficiently strong would lack of the keenness of cross-section, 10 which is so very essential in good propeller design. Therefore, and for another very important reason, which is stated hereafter, I have selected for the blades of the propeller shown herein, a width which is a multiple 15 throughout the different radii of the least widths shown in Fig. 2.

Fig. 3 shows, in plane development, one of the blades of the propeller of double the width throughout of the different radii, as 20 that of Fig. 2, and of the width adopted in Figs. 1, 4, 6, 8 and 9 of the drawings.

The diagram, Fig. 5, shows in plane development of the co-axial cylindrical cross-section, the ideal propeller blade 10—28, 25 corresponding to the least width, at radius 10, of Fig. 2. The driving face 29 thereof is of the circular curvature described by radius 28—30, which latter is made equal to the relative width of the water current, 30 as measured normally to the arc 10—28, of the driving face 29 of the blade section. Therein the sector 10, 28, 30, represents the 35 cross-sectional area under pressure, which is generated by the deflection of the water current from the relative direction normal to radius 28—30, to the relative direction normal to radius 10—30. I have found that in an ideal propeller in which the stream lines of the water current are maintained at 40 a constant distance from the axis of rotation of the propeller and in which the water current is deflected by a driving face of circular curvature, of a radius equal to or less than the relative width of the water current pertaining to the blade section, that 45 the pressure generated within the sectorial area of dynamic pressure is equal or very nearly equal throughout the said sectorial area of dynamic pressure. Therefore, in 50 the diagram, Fig. 5, the pressure generated within the sectorial area 10, 28, 30 of the water current is equal throughout the said area. In the propeller of that description I prevent the radial outward flow of the 55 water completely by providing the blade of the propeller at its outer edge with a shrouding corresponding in form and area to the circumferential area of dynamic pres-

sure or to the sectorial surface 10, 28, 30, Fig. 5. However, in this propeller the circumferential areas of dynamic pressure, corresponding to the smaller radial distances from the axis of rotation of the propeller, are subject to considerably less dynamic pressure than those of larger radius, overlapping them, and thereby the water current within the range of the driving face of the blade suffers considerable deflection from its true path of constant distance from the axis of the propeller by flowing toward 70 the areas of lower pressure located nearer to the axis of rotation of the propeller. To materially reduce these deviations of the water current from the lines of constant distance from the axis of the propeller, I curve 75 the propeller blade in a helically pitched spiral of opposite helical and opposite spiral pitch to the pitch of the driving face of the propeller blade. Thereby the areas of greater dynamic pressure are radially supported by the driving face of the blade, and the centripetal motion of the water current is considerably reduced and the power efficiency and thrust pressure of the propeller are thereby materially increased. To further increase the efficiency of my propeller, 80 I reduce the curvature of the driving face of the blade in the co-axial cylindrical cross-sections by making the radii of curvature a multiple of the relative widths of the 85 water current. This is explained by means of the diagram, Fig. 6, which represents, in plane development, the co-axial cylindrical cross-sections of the propeller blade and of the cross-sectional areas of the water current under dynamic pressure, which correspond to the radii indicated in Fig. 1 by the reference figures 3, 4, 5, 6, 7, 8, 9 and 10, and to like blade sections similarly numbered and shown dotted in one of the propeller blades of Fig. 4. In Fig. 6 the radii of curvature of the driving faces of the 90 blade sections are equal throughout to twice the relative width of the water current pertaining to each blade section, and the blade 100 is made twice as wide throughout the different radii as the ideal blade of least width, of Fig. 2; it, however, is of the width shown in Figs. 1, 3, 4 and 8, so as to deflect the water current in the same degree as the ideal 105 blade of Fig. 2. In Fig. 6 the cross-sectional areas of dynamic pressure appear as truncated sectors, of which 33, 34, 35, 36, is the outer area of dynamic pressure, pertaining to blade section 10, and showing at the same 110 time the true form and size of the shrouding 115 25 of the propeller blades of Figs. 1 and 4. Similarly the truncated sector 37, 38, 39, 40, represents the cross-sectional area of dynamic pressure, as pertains to blade section 120 9. It must be noted, however, that Fig. 6 125

is only a diagram for the graphic determination of the angular position of the blade sections in reference to the axle of the propeller, the direction of which is indicated by line $X-X$, and therefore the blade sections and areas of dynamic pressure are not shown in their correct relative distances from each other. In the cross-sectional areas of dynamic pressure, 33, 34, 35, 36 and 37, 38, 39, 40, of Fig. 6, the dynamic pressure generated through the deflection of the water current is not equal throughout the surface of each sector, like in the full sector area 10, 28, 30, of Fig. 5, but decreases gradually from the driving face of the blade toward the apex of the truncated sectors, although the dynamic pressure is practically constant within each of the stream lines of circular curvature, concentric with the arc of curvature, of the driving face of the blade. Proof of this is as follows: Let the radius of curvature of the cross-sectional line of the driving face of the blade be denoted by R , and any lesser radius of curvature of a stream line of the water current within the same area of dynamic pressure by R' ; the radial distance of the area of pressure from the axis of the propeller by r , the velocity of the water current relatively to the blade section by V , the density of water or other medium by j , and the acceleration due to gravity, by g . Suppose a fine jet of water of the width dR , and of the radial thickness dr , and of rectangular cross-section, enters the surface of the propeller blade tangentially at 28, Fig. 5, with the velocity V , and passes frictionless with uniform velocity along the arc 28, 10, and is discharged tangentially at the edge 10 of the circular arc 28, 10, Fig. 5. By this, each particle of water is subjected to centrifugal action,

$$C = \frac{V^2}{gR}$$

45

and the total centrifugal pressure of this jet normal to the arc 28, 10, is then

$$Cp = \frac{V^2}{gR} \times \text{arc } 28, 10 \times dR \times dr \times j. \quad (I)$$

This first jet of water forms a circular path for a similar second jet of water, which passes along with it under the same velocity, V ; however, at the lesser radius $R-dR$, etc., throughout the whole range of the radius R , all other layers finding a circular guide and bearing on the outer layers of fluid currents of larger radius. Any other jet of the radial width dR traveling on a different or smaller radius than R , say on radius R' , and on a shorter arc 28', 10',

is subjected to greater centrifugal action in inverse ratio of the radii, or as $\frac{R}{R'}$. The total centrifugal pressure in the latter case on the arc 28', 10', is therefore,

$$Cp' = \frac{V^2}{gR'} \times \text{arc } 28', 10' \times dR \times dr \times j. \quad (II)$$

However, the quotients

$$\frac{\text{arc } 28, 10}{R}$$

and

$$\frac{\text{arc } 28', 10'}{R'}$$

75

are equal and constant because the length of the arc diminishes in the same ratio as its radius. Therefore, the total centrifugal pressure Cp' of any similar jet of the width dR , and of any radius R' is constant, or

$$Cp' = \frac{V^2}{gR'} \times \text{arc } 28, 10 \times dR \times dr \times j. \quad (III)$$

Hence, the total centrifugal pressure Cp on the arc 28, 10, due to the whole water current of the width R and the radial thickness dr is:

$$Cp = \frac{V^2}{gR} j \times dr \times \text{arc } 28, 10 \int_0^R dR,$$

or

$$Cp = \frac{V^2}{g} j \times dr \times \text{arc } 28, 10. \quad (IV)$$

95

From the latter equation we get the dynamic pressure per unit area, p , which acts on the cylindrical surface

$$dr \times \text{arc } 28, 10,$$

100

by dividing the right-hand side of this equation with the area

$$dr \times \text{arc } 28, 10,$$

105

thereof, or

$$p = \frac{Cp}{dr \times \text{arc } 28, 10} = \frac{V^2}{g} \frac{dr \times \text{arc } 28, 10}{dr \times \text{arc } 28, 10'}$$

or

$$p = \frac{V^2}{g} j. \quad (V)$$

110

By means of Equation (III) it is proven that each dR of the water current, no matter what the radius of the curvature of its motion, adds an equal increment of pressure on the surface,

$$\text{arc } 28, 10 \times dr.$$

120

Therefore, the unit pressure generated by a water current of radial width less than R is less than that of Equation (V) in ratio of the quotient of the radial dimension of

the current and the radius of curvature of the cross-sectional line of the driving face of the blade. Denoting the radial width of the water current with R_2 and the dynamic pressure per unit area, in this case, with p' , we have:

$$p' = \frac{V^2}{g} J \frac{R_2}{R} \quad (\text{VI})$$

10 which is the dynamic pressure per unit area of the driving face of the propeller blade, of a cross sectional curvature of the radius

$$p' = \frac{V^2}{g} J \left(\frac{\text{arc } 28, 10}{R} dr \int_0^R dR - \frac{\text{arc } 28', 10'}{R'} dr \int_0^{R'} dR' \right) \frac{\text{arc } 28, 10 \times dr}{\text{arc } 28, 10 \times dr}$$

25 or

$$p' = \frac{V^2}{g} J \left(1 - \frac{\text{arc } 28', 10'}{\text{arc } 28, 10} \right).$$

However,

$$30 \quad \frac{\text{arc } 28', 10'}{\text{arc } 28, 10} = \frac{R'}{R},$$

therefore,

$$35 \quad p' = \frac{V^2}{g} J \left(1 - \frac{R'}{R} \right)$$

and

$$R' = R - R_2,$$

or

$$40 \quad p' = \frac{V^2}{g} J \left(1 - \frac{R - R_2}{R} \right) = \frac{V^2}{g} J \frac{R_2}{R} \quad (\text{VI}^a)$$

The above, (VI) is the equation of an equilateral hyperbola, in reference to one of the asymptotes and a line parallel to the other asymptote as axes. By means of Equation (VI) the dynamic pressure p' within any stream line of the truncated areas of dynamic pressure of Fig. 6, can be calculated, by inserting for R_2 , the distance 45 of the stream line, from the apex line of truncation and for R , the radius of curvature of the stream line. Otherwise, for the purpose of generating a predetermined dynamic pressure on the driving face of the 50 propeller blade, the pressure p' and the width of the water current R_2 , must be inserted in this equation, for finding the corresponding radius R of the cross-sectional curvature of the driving face of the blade. 55 The equilateral hyperbolical curves, 3-3, 4-4, 5-5, etc., of the diagram of pressures, Fig. 7, have been calculated in this manner. Through Equation (V) it is evident that the dynamic pressure in the full sector area, 60 28, 10, 30, is equal throughout thereof and the pressure at the apex 30 is the same as the pressure on the driving face 28, 10. Through Equation (VI) it is demonstrated that the dynamic pressure at the apex line of truncation of the areas of dynamic pressure, Fig. 60

15 R , which is greater than the width R_2 , of the water current. The same result is had by integrating Equation (III), between limits R and R' , and dividing by the area,

$$dr \times \text{arc } 28, 10, \quad \text{whereby}$$

$$R' = R - R_2,$$

20

or the radius of curvature of the stream line of the water current at the apex line of truncation, of the truncated area of pressure, Fig. 6. In this way

6, is zero and increases from there toward the driving face of the cross sections of the blade in a ratio set forth in the equilateral hyperbolical curves of the diagram of dynamic pressures, Fig. 7. The velocity V , in 75 the preceding equations, is the resultant of the circumferential velocity and the pitch velocity of the leading edge of the propeller as components. Denoting the radial distance of any element from the axis of the propeller with r , as before, the number of turns per second, at which it is driven with N ; the constant axial pitch at the leading edge of the driving face with T ; the axial pitch velocity with v , and the circumferential velocity of any element of the leading edge of the blade with c , we find:

$$c = N2\pi r \quad (\text{VII})$$

$$v = NT \text{ (constant)} \quad (\text{VIII})$$

90

and

$$V = \sqrt{c^2 + v^2},$$

or

$$V = \sqrt{(N2\pi r)^2 + (NT)^2},$$

95

or

$$V = N\sqrt{(2\pi r)^2 + T^2}, \quad (\text{IX})$$

because c and v act at right angles. Inserting the value of V , of Equation IX, in Equation VI^a, we have

$$65 \quad p' = N^2 J \frac{R_2}{g} (4\pi^2 r^2 + T^2) \quad (\text{VI}^b).$$

100

Denoting the number of uniformly spaced propeller blades with n' ; the pitch angle, at the leading edge of the driving face of any co-axial cylindrical cross-section thereof with X ; the circumferential width of the water current, within a plane normal to the axis of the propeller and pertaining to the blade section at r , with w and the relative width of the water current, measured normally to the leading edge of the blade section with R_2 , as before, then,

$$70 \quad w = \frac{2\pi r}{n'} \quad (\text{X})$$

110

and

$$R_2 = 2\pi r \sin X$$

however,

$$5 \quad \sin X = \frac{NT}{V}$$

therefore,

$$R_2 = \frac{2\pi r}{n'} \frac{NT}{V}$$

10 or by inserting the value of V , as per Equation IX,

$$R_2 = \frac{2\pi r}{n'} \frac{NT}{N\sqrt{(2\pi r)^2 + T^2}}$$

15 or

$$R_2 = \frac{2\pi r}{n'} \frac{T}{\sqrt{(2\pi r)^2 + T^2}} \quad (XI)$$

Substituting the above value of R_2 in 20 Equation VI^b, we have

$$p' = N^2 \frac{J}{g} (4\pi^2 r^2 + T^2) \frac{2\pi r}{n'} \frac{T}{R \sqrt{4\pi^2 r^2 + T^2}} \quad (VI^c)$$

The latter equation gives the dynamic 25 pressure per unit area, of the driving face of the blade, for any value of the radius of curvature R , thereof and when R is made equal to R_2 , the relative width of the water current, then p' , will be the dynamic pressure per unit area of the driving face of least width and radius, as shown in Figs. 2 30 and 5. In that case Equation VI^b will read:

$$35 \quad p' = N^2 \frac{J}{g} (4\pi^2 r^2 + T^2) \frac{R_2}{R}$$

or

$$p' = N^2 \frac{J}{g} (4\pi^2 r^2 + T^2) \quad (VI^d)$$

40 The dynamic pressure per unit area of the driving face of the propeller, in which the radius of curvature of the cross sections of the blade is made a multiple, m , of the least width of the water current, as in Figs. 1, 3, 45 4, 6 and 8, may also be found by multiplying the right side of Equation VI^d with the quotient $\frac{1}{m}$ whereby:

$$50 \quad p' = N^2 \frac{J}{g} \left(\frac{4\pi^2 r^2 + T^2}{m} \right) \quad (VI^e)$$

Further, denoting the distance from the driving face, of any stream line, in the truncated areas of pressure, with R_s the relative width of the water current, pertaining thereto, is $R_2 - R_s$, and the radius of curvature of the stream line is $R - R_s$, and therefore, the dynamic pressure p'' per unit area, pertaining to the stream line, is 55

$$60 \quad p'' = N^2 \frac{J}{g} \left(\frac{4\pi^2 r^2 + T^2}{m} \right) \frac{R_2 - R_s}{R - R_s} \quad (VI^f)$$

In making the calculations for the loca-

tion of the stream lines of equal dynamic pressure, or for ascertaining the ordinates of the pressure curves, like those of Fig. VI, it is not necessary to calculate the actual pressures, for a definite speed N of the propeller, nor for a medium of a definite density j , because it is sufficient to find the relative values of these pressures, which are practically constant for any speed or any density of the medium acted upon. The value

75

$$N^2 \frac{j}{g}$$

of Equation VI^f is constant for all radii and stream lines of the propeller and therefore can be left out of consideration in the calculation of the relative value of the dynamic pressures and the equation may therefore be written:

$$p'' = \left(\frac{4\pi^2 r^2 + T^2}{m} \right) \frac{R_2 - R_s}{R - R_s} \quad (VI^g) \quad 85$$

This equation proves that the relative values of the dynamic pressures throughout the areas of dynamic pressure of the water current, are independent of the speed 90 and solely a function of the constructional dimensions of the propeller, namely the radius r , the axial pitch T , of the leading edge of the blade and the radii of curvature R , of the driving face lines. 95

Fig. 7 is a diagram of the dynamic pressures generated by the circular deflection of the water current throughout of the truncated sector areas of dynamic pressure of the blade sections 3, 4, 5, 6, 7, 8, 9 and 10 100 of Fig. 6. The abscissæ 0—3, 0—4, 0—5, etc., to 0—10, on the horizontal base line thereof represent in double the scale of Fig. 6, the relative widths of the water current measured on lines normal to the cross-sectional curvature of the driving face of the blade, and pertaining to blade sections 3, 4, 5, etc., to section 10. So the horizontal distance, 0—10 represents the radial dimension 34—35, of the truncated sector area of 110 pressure, 33, 34, 35, 36, the horizontal distance 0—9 represents the radial dimension 38—39, of the truncated sector area of dynamic pressure, 37, 38, 39, 40 of Fig. 6, etc. The vertical ordinates, 0—3, 0—4, 0—5, etc., 115 to 0—10, of Fig. 7, indicate the relative dynamic pressures on the driving face lines of the blade sections of Fig. 6. The relative values of these pressures are stated in decimal figures at the right of the vertical ordinate 0—10, wherein the pressure at the line of the driving face of blade section 10 is taken as the unit. The equilateral hyperbolic curves 3—3, 4—4, 5—5, etc., to 10—10, indicate through the dimension of 120 any vertical ordinate which may be drawn 125

from the horizontal base 0—10 to the point of intersection with any one of these curves, the relative dynamic pressures generated within any stream line of the truncated sector areas of dynamic pressure pertaining to the different blade sections.

In an ordinary propeller in which the blade cross-sections pertaining to the different radii are located on a line normal to the axis of the propeller, or in which the driving surface of the blade is dished, the outer areas of greater dynamic pressure are located over and overlap the inner areas of dynamic pressure of the water current. This is clearly evident in the pressure diagram, Fig. 7, and in the diagram, Fig. 6, in which latter, however, for better understanding of this particular case the blade sections pertaining to the smaller radii must be thought to be consecutively located under the outer blade section 10, similarly, the truncated sector areas of pressure must be so transferred with the blade sections. In a propeller of this description a considerable loss of dynamic pressure is caused at the outer radii through the escape of water at the outer edge of the blade, which, however, in my propeller I completely prevent by providing the blade at its outer edge with the shrouding 33, 34, 35, 36, equal to the outer area of dynamic pressure, as shown in Fig. 6. Nevertheless this outer shrouding increases the efficiency of the ordinary propeller only slightly for the reason that the higher pressures maintained at the outer areas of dynamic pressure force part of the outer water current toward the areas of dynamic pressure pertaining to the inner radii, and there, the pressure is increased beyond the normal dynamic pressure so that the water near the hub of the propeller is not only discharged rearward but also in the opposite direction, at the front, and thereby the efficiency of the propeller is very much impaired. However, in my propeller I prevent most of this loss by locating the cross-sections of the propeller blade, pertaining to the different radii, axially and circumferentially in such relative positions to each other that the higher pressures at the areas of dynamic pressure of the outer radii are not located radially outward of the areas of lower dynamic pressure pertaining to the inner radii. The manner in which I accomplish this is herewith explained by reference to the diagram, Fig. 7.

In Fig. 7 the dotted lines 9—9^a, 8—8^a, 7—7^a, etc., to 3—3^a, are parallel to the base line 0—9^a, therefore the point of intersection 9^a, of line 9—9^a, with the pressure curve 10—10, is the point of equal pressure, with the point 9, of maximum pressure, of the

pressure curve 9—9. Likewise the point of intersection 8^a of the line 8—8^a, with the pressure curve 9—9, is the point of equal pressure with the point 8, of maximum pressure, of the pressure curve 8—8, etc., throughout of the diagram. By moving the pressure diagram 0, 9, 9, horizontally to the location 0^a, 9^a, 9^a, in which the dotted curve 9^a—9^a represents the pressure curve 9—9, it is clear that the pressure at point 9^a is the same for both curves 10—10 and 9^a—9^a, and further, it is evident on any other vertical ordinate, for example, on ordinate 41—9^a, that there the pressure 41—10^a, pertaining to curve 10—10 or to the outer area of pressure at radius 10, is less than the pressure 41—9^a, pertaining to curve 9^a—9^a, or to the area of dynamic pressure at radius 9 of the propeller. Similar relations of pressure are established between the pressure curves 9—9 and 8—8 by moving the pressure diagram 0, 8, 8, to the left, so as to locate point 8, of the ordinate 0—8, on point 8^a, of the pressure curve 9—9. By shifting of the pressure diagrams 0, 7, 7, and 0, 6, 6, etc., in the same way, like relations are established in the pressures of the other diagrams of adjacent radii.

In the diagram, Fig. 8, are shown, in plane development of the co-axial cylindrical sections, the driving faces of the blades, pertaining to radii 3, 4, 5, 6, 7, 8, 9 and 10, of Figs. 1 and 2. Therein, the horizontal line X—X, indicates the direction of the axis of rotation, of the propeller, and, at the same time, the axial plane of line 0—10, Fig. 1. Further, the vertical line Y—Y of Fig. 8 indicates a plane, normal to the axis of the propeller and passing through the middle of the driving face of the blade section 10. In Fig. 8, the driving faces of the blade sections are shown with their truncated sector areas of dynamic pressure in their correct angular position, in reference to the axis of rotation X—X of the propeller, and in such a manner that the middle of the driving face 9 is located on the middle radius of the driving face 10, and further, that the middle of the driving face 8 is located on the middle radius of the driving face 9, etc., throughout of the driving faces. Therein, the linear distance 10—9 is equal to the horizontal linear distance of displacement 9—9^a of the pressure diagram 0, 9, 9, to the position 0^a, 9^a, 9^a, of Fig. 7, and the linear distance 9—8, of diagram 8, is equal to the horizontal linear distance of displacement, 8—8^a of the pressure diagram 0, 8, 8, of Fig. 7, etc., throughout, of the diagram, Fig. 8. It must be remembered, however, that the horizontal abscissæ, 0—10, 0—9, etc., of the pressure diagram, Fig. 7, are shown as twice the scale of the Figs. 1,

2, 3, 4, 5, 6 and 8 and, that therefore the dimension lines of displacement, 10—9, 9—8, 8—7, etc., of Fig. 8, appear therein only half as long as the corresponding dimension lines 9—9^a, 8—8^a, 7—7^a of Fig. 7. The vertical ordinate, 10—20, in Fig. 8, represents the circumferential component of the linear distance 10—9, or of the displacement of the blade section 9, in reference to the blade section 10.

In Fig. 1, the arc 10—20, is made of the same length, as the ordinate 10—20, of Fig. 8, and the blade section 9, is located circumferentially, in Fig. 1, by the radial projection of point 20, onto the arc 9—19, of the radius 9. In the same way, the vertical ordinate 20—19, of Fig. 8, represents the circumferential component of the linear distance 9—8, or of the displacement of the blade section 8, in reference to the blade section 9, and, in Fig. 1, the arc 9—19, is made of the same length as the ordinate 20—19, of Fig. 8, and, the blade section 8, is located circumferentially, in Fig. 1, by the radial projection of point 19, onto the arc 8—18. The blade sections 7, 6, 5, 4 and 3, are located circumferentially, in Fig. 1 in like manner, as explained above.

In Fig. 8, the horizontal abscissa 10—49, represents the axial component of the linear distance 10—9, or of the axial displacement of the blade section 9, in reference to the blade section 10; likewise the abscissa 49—48, represents the axial component of the linear distance 9—8, or of the axial displacement of the blade section 8, in reference to the blade section 9. The axial distances of the blade sections shown in dotted lines in Fig. 4, correspond to the dimensions of the horizontal abscissæ, in Fig. 8, wherein the linear dimension 10—49, is equal to the axial distance of the blade section 9, from the blade section 10, etc., whereby finally the blade section 3 is axially distant from the blade section 10, Fig. 4, equal to the linear dimension 10—43, of Fig. 8.

Through the diagrams, Figs. 7 and 8, it is evident that the dynamic pressure, at point 20, of Fig. 1, is equal to the dynamic pressure at the point 9, further that the dynamic pressure at the point 19, is equal to that at the point 8, etc. Therefore, the dynamic pressure, within the stream line, pertaining to the point 20, is equal to the dynamic pressure, within the stream line pertaining to the point 9; similarly the dynamic pressures, pertaining to both of the stream lines of points 19 and 8, are equal, and therefore, the dynamic pressure, within the stream lines, located radially between any one pair of these points, or within radial proximity thereof is equal throughout of them, or nearly so. In this manner, the dynamic

pressures, pertaining to the areas of dynamic pressure, of the different radii, are located so as to completely prevent centrifugal motion of the water current, and thereby the efficiency of the propeller is materially increased. Nevertheless, in the arrangement of the cross sections of the blades described above, the dynamic pressures near the apex of the truncated sector areas of dynamic pressure, are not in perfect radial balance.

This is apparent in the pressure diagram, Fig. 7, by comparison of the pressure curve 10—10 of the outer radius 10 of the propeller, with the pressure curve 9^a—9^a, of the radius 9. Therein the linear dimension of the vertical ordinate 5—50, represents the pressure at point 50 of the pressure curve pertaining to the radius 10 of the propeller, and at the same location, the linear dimension of the vertical ordinate 5—42, represents the pressure at point 42, of the pressure curve 9^a—9^a, at the radius 9 of the propeller and the linear dimension 50—42, in the same location, expresses the difference of dynamic pressure of the stream lines, pertaining to radii 9 and 10, of the propeller, at this point. This difference of pressure causes part of the water, near the apex or the pressure areas, to move centrifugally outward, whereby the dynamic pressure at the inner radii is reduced. This deficiency, however,

I partially avoid, in some cases, by the shifting of the blade sections, of only a fraction of the linear dimension of the lines 9—9^a, 8—8^a, 7—7^a, etc., of Fig. 7, for example, of half of these distances, as indicated, for one instance, by the pressure curve 9^b—9^b, pertaining to radius 9, which is shifted through the horizontal distance 9—9^b, shown dotted, in Fig. 7. In this manner, the radial outward flow of water from the apex of the pressure areas is reduced and compensated for by the inward flow of water, near the surface of the blade, where then the dynamic pressures, at the outer radii, are slightly greater than at the inner radii. Thereby, the water pressures, at the areas of pressure of the different radii are very nearly preserved in the condition of radial balance, necessary for the maximum efficiency of the propeller.

I have found that the performance of propellers is very materially affected by slight imperfections of the driving face of the blade, that the latter must be of true form from the leading edge to the rear edge, and that the necessary keenness of the blade section must be provided for by curves at the back of the blade. This is shown in Fig. 9, in which 51 is the driving face of the blade formed by the circular curve 33—34, reaching from the leading edge 34 to the point of egress 33. The blade

has its greatest thickness at the rear, between the points 52 and 10, and is made tapering, from the point 10 to the point 53, from which latter the front cutting edge 5 is formed by the convex-concave curve 53-34, as indicated by the prolongation 54 of the curve, in dotted line. This cross sectional form of the blade reduces the body resistance thereof considerably without detracting from its strength. The rear edge 10 of the blade is simply formed by the convex curve 33-52.

Fig. 10 shows enlarged a cross section of the shrouding 25 of the propeller, on the line Z-Z of Fig. 4. Therein, the inner face 55 is of true circular curvature from the leading edge 56 to the edge of egress 57; the leading edge being formed on the outside thereof by the concavo-convex curve 20 56-59, as indicated by the dotted line prolongation 58, and the rear edge being formed by the convex curve 57-60. The outer stationary shrouding 27, of Figs. 1 and 4, serves principally as a protector from the 25 disturbing action of side currents, for the purpose of avoiding sudden shocks and vibrations. In some cases, for example, under very high rotative speeds or great dynamic pressure, the blades cannot be provided with 30 the shrouding 25, and then I make use of the outer stationary shrouding 27, to prevent the radial escape of water from the outer area of pressure.

The propeller principally exemplified 35 herein, has blades with driving faces of a cross sectional curvature, corresponding to a constant multiple of the relative width of the water current throughout of the different radii. Further, I have explained my 40 invention by means of a propeller in which the pitch of the leading edge, as well as the pitch of egress is constant throughout of the different radii, and likewise I have referred to a propeller with four blades. 45 However, I do not limit my claims to these particular proportions or features, as it is self-evident to those skilled in the arts of engineering that the radii of curvature of the cross sectional lines of the driving face 50 of the blade can be made of any variable, instead of a constant multiple, of the relative widths of the water current, throughout of the different radii of the propeller, and further, that the pitch either of the leading edge or the pitch of egress of the 55 blade, or both, may be made to differ throughout of the radii; and that the propeller may be carried out with any number of blades, instead of four.

60 In many cases, it is difficult to make the blades of the propeller sufficiently strong near the hub and at the same time to retain the keenness of the cross section. For that

purpose, I considerably increase the pitch of egress, near the hub, as indicated by the 65 dotted lines 55, 56 and 57, of the blade sections 3, 4 and 5, of Fig. 6. Further, in the diagram, Fig. 8, the blade sections are located on a curve 3-10, this, however, is not a necessary feature of my invention, and 70 in some cases I locate these sections in the plane development of the propeller, either in a straight line or in a line of opposite curvature to that shown in Fig. 8. Further, I do not limit the claims pertaining to this 75 invention to a propeller with blade cross sections having a concave driving face, because I have found that blades of true pitch having a straight line driving face in the plane development of the cross section thereof act like blades having a concave driving face and deflect the current in circular stream lines, although imperfectly so.

Having explained the operation of my propeller, in reference to its application for 85 ship propulsion and in reference to its action in water, I do not limit my claims to that purpose, for the reason that it is advantageously applicable to a great variety of other devices, as flying machines, fans, rotary 90 pumps, air compressors and steam, gas and air turbines, used for the generation of power.

My propeller is very efficient within a very large range of pitch angles and it can 95 be used with very small pitch angles and high rotative speeds, without a material reduction of its high efficiency. It is particularly suitable for the propulsion of ships, by means of steam turbine motors, because it 100 can be efficiently operated under the higher rotative speeds essential for the most economical performance of the latter. Further, my propeller works without pumping action and therefore does not add to the stern 105 resistance of the ship.

I am aware that heretofore, the blades of propellers have been provided with shrouding on the driving face thereof; however, I am not aware that these shroudings have 110 been extended sufficiently, heretofore, from the driving face of the blade, so as to fully or even approximately cover the area of dynamic pressure pertaining thereto.

It seems that the mechanical principle of 115 the areas of pressure, as disclosed therein, has not been known, or understood, and practically applied in propeller construction heretofore, and I claim particularly as novel and basic that feature of my invention, 120 which consists in the special selection of the radii of the cross sectional curvature of the driving face of the blade, for the purpose of augmenting the dynamic pressures of the 125 water current at the different radii of the propeller, so as to establish the radial bal-

ance of the dynamic pressures throughout of the water current.

Having thus described my invention I claim as new and desire to secure by Letters

5 Patent:

1. In a rotary propeller, a propeller blade having a shrouding on the driving face of the blade, formed of such a size relative to the size of said propeller blade as to have an 10 area approximately equal to the circumferential area of the water current brought under dynamic pressure by said propeller, adjacent to said shrouding.
2. In a rotary propeller, a propeller blade 15 having a shrouding on the driving face of the blade, said shrouding having approximately sector form constructed of such a size relative to the size of the propeller blade as to have an area approximately equal to the 20 circumferential area of the water current under dynamic pressure, adjacent to said shrouding.
3. In a rotary propeller, a propeller blade having a shrouding on the driving face of the blade, formed of such a size relative to the size of the propeller as to have a surface 25 projecting from the driving face of the blade a distance approximately equal to the width of the water current under dynamic pressure, adjacent to said shrouding.
4. In a rotary propeller, a propeller blade curved in a helically pitched spiral of opposite helical and opposite spiral pitch to the pitch of the driving face of the blade.
- 35 5. In a rotary propeller, a blade bent axially in the opposite direction to the direction of thrust of said blade, and also bent circumferentially so as to have the driving face of said blade of convex curvature, and
- 40 a shrouding member projecting rearwardly from the outer end of said blade to a point substantially in line with the base of said blade.
6. In a rotary propeller, a propeller blade 45 curved in a helically pitched spiral of opposite helical and opposite spiral pitch to the pitch of the driving face of the blade, and a shrouding on the driving face of the blade.
- 50 7. In a rotary propeller, a propeller blade curved in a helical pitched spiral of opposite helical and opposite spiral pitch to the pitch of the driving face of the blade, and a shrouding arranged with respect to the 55 blade to prevent the radial escape of water from the outer area of dynamic pressure.
8. In a rotary propeller, a propeller blade curved in a helically pitched spiral of opposite helical and opposite spiral pitch to the 60 pitch of the driving face of the blade, a shrouding on the driving face of the blade, and a stationary cylindrical shrouding surrounding the propeller.
9. In a rotary propeller, a propeller blade so formed as to have a driving face of concave curvature in the co-axial cylindrical cross sectional lines thereof, the radii of curvature of which are greater than the radial widths of the water current area pertaining to each blade section and which are 65 such as to locate, or approximately locate, the stream lines pertaining to the area of dynamic pressure of one blade section in radial projection with the stream lines of equal relative dynamic pressure, pertaining to the 70 area of dynamic pressure of another blade section of greater or less radial distance from the axis of the propeller.
10. In a rotary propeller, a forwardly extending propeller blade and a shrouding 80 member connected to the outer ends of the propeller and extending rearwardly therefrom, said shrouding member being formed of an area approximately equal to the circumferential area of the water current 85 brought under dynamic pressure by said propeller adjacent said shrouding member.
11. In a rotary propeller, the combination with a ring-shaped stationary shrouding member, of a propeller co-acting therewith 90 formed with a blade positioned substantially within said stationary shrouding member and formed with a shrouding member extending parallel to the axis of the propeller.
12. In a rotary propeller, a propeller blade 95 having a driving face of concaved curvature, in the co-axial cylindrical cross sectional lines thereof, the radii of curvature of which are greater than the radial width of the water current area pertaining to each blade 100 section and increase from the hub to the outer edge of the blade in such a manner so as to establish or approximately establish in radial projection stream lines of equal relative dynamic pressure in the areas of dynamic pressure pertaining to the cross 105 sectional lines of the driving face of the blade.
13. In a rotary propeller, a hub and a blade extending therefrom so formed as to have a driving face of concave curvature in 110 the co-axial cylindrical cross sectional lines thereof, the blade being curved circumferentially and axially so as to successively locate or approximately locate the middle of the driving face lines of the blade cross sections of the lesser radii of the propeller in radial projection of points of the radial lines pertaining to the middle of the driving face lines of the blade sections at the greater 115 radii.
14. In a rotary propeller, a hub and extending therefrom a plurality of blades having driving faces of concaved curvature, in the co-axial cylindrical cross sectional lines thereof, the radii of curvature of which are 120 greater than the radial width of the water 125

- current areas pertaining to the blade sections and increase from the hub to the outer edge of the blade in such a manner so as to locate or approximately locate in radial projection stream lines of equal relative dynamic pressure in the areas of dynamic pressure pertaining to the cross sectional lines of the driving face of the blades, the blades being curved circumferentially and axially 10 so as to successively locate or approximately locate, the middle of the driving face lines of the blade cross sections of the lesser radii of the propeller, in radial projection of points of the radial lines pertaining to the 15 middle of the driving face lines of the blade sections at the greater radii of the propeller.
15. In a rotary propeller, a hub and extending therefrom a plurality of blades of constant axial pitch both at the leading edge 20 and the rear edge and so formed as to have driving faces of concave curvature in the coaxial cylindrical cross sectional lines thereof,

the radii of curvature of which are multiples of the radial widths of the cross sectional water current areas pertaining to each blade 25 section and the widths of the blades at the different radii of the propeller of which correspond to like multiples of the widths of the ideal blade of least width in which the radii of the cross sectional lines of the driving face are equal to the radial width of the cross sectional water current areas pertaining thereto and in which the axial pitch of both the leading edge and the edge of egress 30 are the same as in the blades of multiple 35 width.

In testimony whereof I have signed my name to this specification in the presence of two subscribing witnesses.
